IGNITION SYSTEM.

1,338,360.

Specification of Letters Patent. Patented Apr. 27, 1920.

Application filed April 19, 1917. Serial No. 163,172

To all whom it may concern:

Be it known that we, FRANK CONRAD, a citizen of the United States, and a resident of Pittsburgh, in the county of Allegheny and State of Pennsylvania, and J. STANLEY KINNEY, a citizen of the United States, and a resident of Wilkinsburg, in the county of Allegheny and State of Pennsylvania, have invented a new and useful Improvement in Ignition Systems, of which the following is a specification.

Our invention relates to ignition systems, and it has for its object to provide an arrangement whereby the currents traversing the contact members of interrupters shall be automatically reversed after each operation of the interrupters.

Ignition interrupters, as commonly constructed, comprise movable and stationary contact members that are permanently connected to the respective poles of batteries or magnetos, as the case may be. When the contact members of an interrupter are separated to open the primary circuit, an arc follows in which the current always flows from the one contact member to the other. The result is to cause the one contact piece to become pitted because of the surface metal being carried away and to produce projections on the surface of the other contact member because of the metal being deposited during the existence of an arc. The efficiency of the interrupter is decreased by the resulting poor electrical contact between the irregular surfaces of its contact members, and the life of the mechanism is correspondingly shortened.

It has been proposed, heretofore, to reverse the electrical connections of the interrupter in order to prevent the abnormal conditions described above but such arrangements operate to reverse not only the electrical connections of the interrupter but also those of the induction coil and other elements of the ignition circuit. It has been found that such arrangements possess a number of disadvantages that are eliminated by a system constructed in accordance with our invention.

A material disadvantage in connection with the arrangements of the prior art resides in the fact that the spark at the electrodes of a spark plug always occurs adjacent to the one or the other of the electrodes,

depending upon the direction of the currents traversing the primary and the secondary circuits. The central electrode of the spark plug consists of a small rod of metal, while the other electrode is either adjacent to, or is constituted by, the outer ring or bushing that is in engagement with the engine cylinder.

When the spark occurs adjacent to the larger body of metal, it is cooled much more rapidly, and hence, it is of lower heat intensity and of shorter duration than one occurring adjacent to the central electrode. The reversal of the current through the primary coil after each operation of the interrupter causes alternate ignition sparks to be produced adjacent to the outer electrode of the spark plug. Accordingly, one-half of the sparks are of less heat intensity than the other half, and uniformity of operation of the engine is not possible.

We provide a system in which the electrical connections of the interrupter contact members are automatically reversed after each operation. The tendency to transfer metal from one contact member to the other is thus neutralized and the result is not only to materially lengthen the life of the interrupter but to increase its efficiency during operation by maintaining substantially plane surfaces upon the faces of the contact members.

The reversing switch is so arranged that the electrical connections of the interrupter only are changed and the current always flows in the same direction through the primary and the secondary windings of the induction coil. The central electrodes of the spark plugs are so connected that they constitute the negative electrodes of the spark gap and, accordingly, the ignition sparks always occur adjacent to the central electrodes. This arrangement insures that all of the sparks shall be of maximum heat value and duration.

In the accompanying drawing, Figure 1 is a view, in section, taken on line I—I of Fig. 2 of an interrupter constructed in accordance with our invention, the cover being removed. Fig. 2 is a plan view of the mechanism shown in Fig. 1, parts being broken away. Fig. 3 is a view, partially in elevation and partially in section, of a lever embodied in the mechanism shown in Figs.

1 and 2. Figs. 4 and 5 are, respectively, side and end views of the lever shown in Fig. 3. Fig. 6 is a plan view of the contact segments constituting parts of the reversing mechanism. Fig. 7 is a diagrammatic view of circuits and apparatus embodying our invention. Similar reference numerals are employed to designate corresponding parts throughout the drawing.

10 Referring particularly to Figs. 1 and 2, a stationary member 1, which may be a part either of a magneto or of a direct-current dynamo-electric machine, supports a hollow cylindrical member 2 that is adapted for 15 rotative movement relatively thereto. The member 2 constitutes the casing of an interrupter mechanism.

A shaft 3, which may be, for example, the armature shaft of a dynamo-electric machine, carries the rotatable portion of the interrupter mechanism. A sleeve 4, which surrounds a reduced portion of the shaft 3, is integral with a disk or plate member 5. A stationary contact member 6 is mounted 25 upon, and insulated from, the disk 5.

A movable contact member 7, which coacts with the stationary contact member, is carried by a lever 8 that is pivotally mounted, at an intermediate portion, upon a pin 9. 30 A spring 10, which is connected, at one end, to a stationary member 11, is connected, at the other end, to a bar 12 that is rigidly secured to the lever 8.

The member 11 has an integral projecting portion 13 which extends adjacent to one end of the lever 8. A strip of leather 14, that is slightly wider than the projecting portion 13, is provided with two transverse slits near its respective ends through which the projection may be inserted. The leather strip is placed on the projection 13 in such manner that the intermediate and end portions of the former are respectively upon opposite sides of the latter. The leather strip may be 45 retained in position by cement, shellac or other suitable adhesive material. The intermediate portion of the strip 14, which is parallel to the projection, forms a resilient stop for the lever 8.

50 Reference may now be had to Figs. 3, 4 and 5, in which the lever member 8 is illustrated. As shown in Figs. 2 and 4, the lever 8 is of substantially U-shape. It comprises two side members 15 and 16 that may be 55 punched from any suitable sheet material, such, for example, as steel. Corresponding end portions of the members 15 and 16 are bent at right angles to the plane of the members in opposite directions. These projecting portions are of such length as to overlap each other, as shown in Figs. 3 and 5. The 60 movable contact member 7 is then riveted or otherwise suitably fastened to these portions.

The opposite end portions of the members 15 and 16, which are also bent inwardly,

are of such length that a small space separates them. A block 17, of suitable insulating material, such, for example, as fiber, is rigidly secured to the members 15 and 16, between their end portions, by suitable means, such, for example, as rivets or pins 18. The bar 12, to which the spring 10 is connected, extends between the side members 15 and 16 and is riveted to these members at its respective end portions.

75 As best shown in Fig. 1, the intermediate portions of the side members 15 and 16 are connected by a tubular shoulder pin 20, the end portions of which are riveted in a suitable manner. A bearing sleeve 21, which is 80 within the shoulder pin 20, is of insulating material. Insulating washers 22 and 23 are at each end of the pin 20 in order to effectively insulate the latter from its supporting means.

85 The means for reversing the electrical connections of the interrupter contact members 6 and 7 comprises a pair of contact segments 24 and 25, shown in Fig. 6, that are secured to the disk 5 and insulated therefrom. The ends of the contact segments 24 and 25 are separated by smaller segments 26, for a purpose to be later described. The contact segments 24 and 25 are respectively electrically connected to the interrupter contact members 6 and 7. The contact segments 24 and 25 coact with a pair 90 of stationary brushes 27 and 28, only one of the brushes appearing in Fig. 1.

95 The member 1 is provided with a chamber 100 29, within which is located a condenser 30. The chamber 29 communicates with the interior of the casing member 2 by means of an opening 31 in the base member 1 and a notch or slot 32 in the casing member 2. 105 This arrangement provides that a conductor may extend from the condenser 30 to the brush 28 to electrically connect these parts.

110 The stationary portion of the interrupter comprises two cams 33 that are located diametrically opposite to each other within the casing member 2 and are rigidly secured thereto. The cams 33 are within the path 115 of movement of the block 17 of insulating material and effect the disengagement of the contact members twice during each revolution of the shaft 3. The time at which the sparks occur in the several engine cylinders may be adjusted by means of an arm 34, only a portion of which is shown, that 120 controls the angular position of casing 2 and the cams 33. The arm 34 is operatively connected to the usual spark lever that is mounted upon the steering column of an automobile.

125 Reference may now be had to Fig. 7, in which the electrical connections of the various elements of an ignition system embodying our invention are diagrammatically shown. A source of current, which may be,

for example, a storage battery 35, is connected in series with the primary winding 36 of an induction coil. The primary circuit of the ignition system comprises, also, the brushes 27 and 28, contact segments 24 and 25, spring 10, lever 8, contact segments 6 and 7, and condenser 30.

The secondary circuit of the ignition system comprises the secondary winding 37 of the induction coil, a distributor 38 and spark plugs 39 that are respectively connected to the several contact segments of the distributor 38.

It may be assumed that the shaft 3 is rotating in a counter-clockwise direction, Fig. 2, and that the various parts are in their respective positions in which they are illustrated, Fig. 2. The contact members 6 and 7 are in engagement and the fiber block 17 occupies a position between the cams 33 with which it coacts. It may be assumed, further, that the brushes 27 and 28 respectively engage the contact segments 24 and 25. Current then traverses the primary circuit of the ignition system which extends from the battery 35, through the primary winding 36 of the induction coil, brush 28, contact segment 25, contact members 6 and 7, lever 8, spring 10, contact segment 24, brush 27, which is grounded, and thence to the other terminal of the battery which is also grounded.

When the bearing block 17 engages the inclined end portion of one of the cams 33, the lever 8 is moved about its point of pivotal support to separate the contact members 6 and 7 and thereby open the primary circuit traced above. An electromotive force of high value is inducted in the secondary circuit, and a spark occurs across the terminals of the spark plug 39 that is connected to the rotatable contact member of the distributor 38.

Further rotation of the shaft 3 and the mechanism carried by it causes the contact segments 24 and 25 to be disengaged from the respective stationary brushes 27 and 28 and to respectively engage the other brushes. The segments 26, which are between the end portions of the contact segments 24 and 25, are not electrically connected to any of the elements of the ignition system. They are inserted for the purpose of providing a continuous surface for the brushes 27 and 28 and for insuring that the brushes may be entirely disconnected from the segments 24 and 25 during the period of reversal of the connections.

The primary circuit is again closed at contact members 6 and 7 when the bearing block 17 moves off the cam 33 with which it was in engagement. Current then flows in the opposite direction through that portion of the primary circuit which is between the brushes 27 and 28. When the

block 17 engages the second cam 33 to effect the disengagement of contact members 6 and 7, the arc which follows between the contact members 6 and 7 will be produced by a current having a direction opposite to that of the preceding arc, and an opposite effect will thereby be produced upon the respective interrupter contact members.

The point in the engine strokes at which the various sparks occur may be adjusted, as desired, by varying the angular position of the cams 33 to cause the block 17 to engage them earlier or later.

The arrangement constructed in accordance with our invention possesses a number of advantages. The life of the mechanism is materially prolonged by periodically reversing the direction of the current through the interrupter contact members. As previously set forth, the reversing of the current through the interrupter contact members does not, in any way, affect the efficiency of operation since the polarities of the spark plugs are unchanged.

The various parts of the interrupter mechanism are simple in construction and few in number. The moving parts are of relatively small weight in order that they may oscillate with great rapidity in case they are used in connection with engines which operate at high speeds. The interrupter lever is so arranged as to possess great strength while it is composed of relatively light materials. The above and other advantages will be apparent to those skilled in the art to which our invention appertains.

We claim as our invention:

1. In an interrupter, the combination with a pair of relatively movable contact members, of a lever for actuating one of said contact members, said lever comprising two plate members having rigidly connected end portions, to which one contact member is secured and a pivot upon which the lever is mounted having its axis transverse to the planes of the main portions of the plate members.

2. In an interrupter, the combination with a pair of relatively movable contact members, of a lever for actuating one of said contact members, said lever comprising two substantially similar members having bent overlapping end portions that are rigidly connected, and form a support for one of said contact members, a member for pivotally supporting said lever, and a spacing member between said lever members and surrounding said supporting member.

3. In an interrupter, the combination with a pair of relatively movable contact members, of a lever for actuating one of said contact members, said lever comprising two rigidly connected plate members arranged in parallel relation and spaced apart, a bar ex-

- tending between said plate members, and a spring secured to said bar.
4. In an interrupter, the combination with a pair of relatively movable contact members, of a lever for actuating one of said contact members, said lever comprising two plate members having bent end portions to which said one contact member is secured, and a pivot upon which the lever is mounted having its axis transverse to the planes of the main portions of the plate members.
5. In an interrupter, the combination with a pair of relatively movable contact members, of a lever for actuating one of said contact members, said lever comprising two plate members, a block of insulating material between said plate members and secured thereto at one end thereof, and a member movable relatively to said block for coacting therewith.
6. In an interrupter, the combination with a pair of relatively movable contact members, of a lever for actuating one of said contact members, said lever comprising two plate members spaced apart and connected at their respective end portions, means for pivotally supporting said lever, a block of insulating material secured to said lever at one end thereof, and means coacting with said block for actuating said lever.
7. In an interrupter, the combination with a pair of relatively movable contact members and a lever for actuating one of said contact members, of a spring connected to said lever, and a member for supporting
- said spring having an integral portion for constituting a stop for said lever.
8. In an interrupter, the combination with a pair of relatively movable contact members and a lever for actuating one of said contact members, of a stop for said lever comprising a bar and a strip of resilient material having openings through which said bar extends.
9. In an interrupter, the combination with a rotatable member and a pair of relatively movable contact members carried thereby, of an electrical circuit comprising said contact members and means for reversing the connections of said contact members, said reversing means comprising a pair of contact segments carried by said rotatable member and electrically connected to the respective contact members, and a pair of stationary brushes for successively engaging the respective contact segments.
10. In an interrupter, the combination with a rotatable member and a pair of relatively movable contact members carried thereby, of a pair of contact segments carried by said rotatable member and electrically connected to said contact members, and a pair of stationary brushes for successively engaging the respective contact segments.

In testimony whereof we have hereunto subscribed our names this 3rd day of April, 1917.

FRANK CONRAD.
J. STANLEY KINNEY.
